INVENTOR,
VICTOR E. STARNER.

By Martin P. Smith, Atty.

UNITED STATES PATENT OFFICE.

VICTOR E. STARNER, OF BELL, CALIFORNIA.

TOWEL BAR.

Application filed October 5, 1926. Serial No. 130,594.

My invention relates to a towel rail and has for its principal object the provision of a relatively simple and practical rail that may serve as a hanger and support for towels, wash cloths, and the like, and which rail is constructed so that the towels or wash cloths may be positioned upon or removed from the rail by a relative endwise movement and which provision greatly facilitates the handling of the towels or wash cloths and minimizes the liability of the towels and wash cloths from dropping off the rail or bar while placed in position thereon or removed therefrom.

The types of towel bars or rails now in general use are connected at both ends to supporting brackets or to the wall and such arrangement makes it necessary to place the towels and wash cloths on the rail or bar by a vertical movement and where two or more towels or wash cloths are arranged on a rail having both ends secured to the wall or brackets and one towel or wash cloth is removed, it very frequently happens that the adjacent towel or wash cloth will be accidentally withdrawn from the supporting rail with the result that the accidentally withdrawn towel or wash cloth will drop onto the floor or into the bath tub or washbowl over which the towel-supporting bar is positioned.

I propose to overcome the objectionable results just noted by providing a towel-supporting rail or bar that is secured to the wall or support at one end only, or, in the event of a double bar, at its center, and which arrangement enables the towels and wash cloths to be positioned upon and removed from the bar by a relative endwise movement.

A further object of my invention is to provide a towel bar having an adjustable base portion that is constructed so that it may be very firmly anchored to the wall structure, thus imparting to the fixture strength and stability and effectually preventing removal of the fixture unless the entire wall structure is torn away.

Further objects of my invention are to provide a towel-supporting bar or rail of the character referred to that is inexpensive of manufacture and which, when properly con-

structed, presents a neat and finished appearance.

With the foregoing and other objects in view, my invention consists in certain novel features of construction and arrangement of parts that will hereinafter be more fully described and claimed and illustrated in the accompanying drawing, in which—

Fig. 1 is a perspective view of a towel-supporting bar embodying the principles of my invention.

Fig. 2 is a horizontal section taken through the base portion of the towel bar and showing the means for attaching said bar to the wall structure.

Fig. 3 is a perspective view of a fixture embodying the principles of my invention and which is of the duplex or double bar type.

Fig. 4 is a plan view showing a pair of the towel bars or rails positioned adjacent to each other with their ends spaced apart to permit the insertion or removal of towels and wash cloths.

Fig. 5 is a plan view of a pair of the bars or rails arranged with the base plates or brackets adjacent to each other and the bars or rails projecting in opposite directions.

Referring by numerals to the accompanying drawings, and particularly to the construction illustrated in Figs. 1 and 2, 10 designates a base plate, preferably formed of metal of any desired size and shape and formed integral with and projecting forwardly from one end of this base plate is a short horizontally disposed curved arm or bracket 11 with which is formed integral a horizontally disposed rail or bar 12, the latter being of any desired length and either square, round, or polygonal in cross section. This bar may be either solid or tubular and its free end is provided with an enlarged head or knob 13 that may be formed integral with the bar or separately formed and attached thereto in any suitable manner.

To firmly anchor the rail or bar to a wall, the base plate 10 is provided with a pair of rearwardly projecting studs 14, the rear portions of which are threaded and said rear portions extend through apertures that are formed in a plate or bar 15, the latter being

secured in any suitable manner, preferably by means of screws 16, to the wall studs S or to a wall member that is arranged between the studs.

5 Nuts 17 mounted on the threaded portions of the studs 14 engage plate 15, thereby adjustably and rigidly connecting the base plate 10 to anchor plate 15 and the space between said base plate and anchor plate accommodates the wall finishing material such as metal lath, plaster, tiling and the like.

By adjustably mounting the studs in plate 15, the fixture can be readily adjusted for the accommodation of tile or wall finishing members of different thicknesses and the anchoring of the fixture to the embedded base plate 15 imparts strength and stability to the fixture and effectually prevents its removal unless the entire wall structure is broken away.

20 In the duplex form of towel supporting bar illustrated in Fig. 3, 18 designates a base plate that may be anchored to the wall in any suitable manner and projecting forwardly from the center of said base plate is a short 25 shank 19. Formed integral with and projecting in opposite directions from the forward end of this shank 19 are aligned bars or rails 20, the outer ends of which are provided with knobs or heads 21. These knobs 30 may be formed integral with the rails or they may be separately formed and secured to the rails in any suitable manner. Rails 20 may be of any desired and convenient length and they may be of uniform diameter throughout 35 their lengths or they may taper toward their outer ends as illustrated.

I prefer to form the base plate 18, shank 19, and rails 20 from a single piece of metal, preferably by casting. The shank 19 that 40 projects forwardly from base plate 18 should be about three or four inches in length and thus the rails or bars are positioned a corresponding distance in front of the wall to which the base plate 10 is attached. The rails 45 20 afford convenient hangers for towels, wash cloths, and the like, and, as the outer ends of said rails are spaced apart from the wall, the towels and wash cloths may be readily applied to or removed from the rails by end- 50 wise movement relative thereto.

The form of rail or bar illustrated in Figs. 1 and 2 may be used singly or in pairs as illustrated in Figs. 4 and 5, and as the free end of the bar is spaced apart from the wall 55 to which the base plate on the other end of the bar is attached, the towels or wash cloths may be positioned upon or removed from the bar by a relative endwise movement, rather than by a vertical movement where both ends 60 of the rail or bar are connected to the wall or brackets.

Thus it will be seen that I have provided a towel supporting bar or rail that is relatively simple in structure, having great 65 strength and stability, readily adjustable so

as to accommodate different thicknesses of wall finish and tiling, said bearing or rail being constructed so as to be very firmly anchored to the wall structure and consequently preventing ready removal and which towel 70 supporting bar or rail presents a neat and finished appearance and is very effective in performing its intended functions.

It will be understood that minor changes in the size, form and construction of the various parts of my improved towel-supporting bar or rail may be made and substituted for those herein shown and described without departing from the spirit of my invention, the scope of which is set forth in the appended 80 claims.

I claim as my invention:

1. The combination with an anchor plate that is adapted to be embedded in a wall structure, of means for rigidly securing said anchor plate to parts of the wall structure, a plate adapted to occupy a portion on the face of the wall structure in which the anchor plate is embedded, threaded studs formed integral with said plate, which threaded studs pass through and are adjustably connected to the anchor plate, a short arm formed integral with and projecting forwardly from said plate, a horizontally disposed rail formed integral with and projecting laterally from said short arm, said rail being spaced apart from and lies parallel with the face of the wall structure, and the free end of said rail being spaced apart from the wall structure in order to provide an opening 100 through which articles may be moved lengthwise of the rail when positioned thereon, or removed therefrom.

2. A towel supporting fixture comprising an anchor plate adapted to be embedded in a wall structure, means for rigidly fixing said anchor plate to parts of the wall structure, a plate adapted to occupy a position on the face of the wall structure in which the anchor plate is embedded, threaded studs formed integral with and projecting rearwardly from said plate through the anchor plate, nuts located on said threaded studs for clamping the same to said anchor plate, a rail formed integral with and projecting laterally from said plate, said rail occupying a horizontal position in front of and parallel with the wall structure, and the free end of said rail being spaced apart from the wall structure to permit objects to be positioned upon or removed from said rail by a relative longitudinal movement.

3. A towel supporting fixture comprising an anchor plate that is adapted to be embedded in a wall structure, means for rigidly fixing said anchor plate to parts of the wall structure, a base plate adapted to be positioned on the face of the wall structure in which the anchor plate is embedded, threaded studs projecting rearwardly from said 120

base plate through the anchor plate, nuts on
said threaded studs for clamping the same
to said anchor plate, a short arm projecting
forwardly from said base plate, a horizon-
5 tally disposed rail projecting laterally from
said short arm, said rail occupying a horizon-
tal position in front of and parallel with the
wall structure, and the free end of said rail
being spaced apart from the wall structure
to permit objects to be positioned upon or 10
removed from said rail by a relative longitu-
dinal movement.

In testimony whereof I affix my signature.
VICTOR E. STARNER.
